W.H. Atkins.
Pent Lock.

No. 14,848.

Patented May 13 1856

Inventor
W.H. Atkins

UNITED STATES PATENT OFFICE.

WILLIAM H. AKINS, OF BERKSHIRE, NEW YORK.

LOCK.

Specification forming part of Letters Patent No. 14,848, dated May 13, 1856; Reissued November 8, 1864, No. 1,806.

To all whom it may concern:

Be it known that I, WILLIAM H. AKINS, of Berkshire, in the county of Tioga and State of New York, have invented a new and useful Improvement in Locks for Doors, Safes, Banks, &c., of which the following is a full, clear, and exact description, reference being had to the accompanying drawing, in which—

10 Figure 1 represents a front elevation of such of its parts as are on the outside of the door, the latter being represented as broken off. Fig. 2 represents an elevation of the rear side of the lock as secured to the door, 15 showing the bolt protruded into the recess of the staple when locked, the bolt of the latter being removed. Fig. 3 represents a longitudinal section of the same taken through the line $\alpha\alpha$ of Fig. 2; and Fig. 4 a 20 view of Fig. 2 with the cap removed. Fig. 5 represents a side elevation of the staple with the catch bolt in position when the door is locked; and Fig. 6 a section of the same, but having the bolt raised for the purpose of 25 opening the door from the inside. Fig. 7 represents a side elevation of the lock bolt and slotted disks, showing their relative positions when the former is retracted to unlock the door; and Fig. 8 a plan of the under 30 side of the lock and horizontal section of the door taken through the line $\alpha\alpha$ Fig. 2. And Figs. 9, 10, 11, and 12, represent side elevations or plans of the slotted disks.

The object of my invention is to provide 35 a lock for the prevention of burglary, that, from its simplicity of construction and trifling cost will enable it to supersede the locks now in common use, it being adapted as well to doors as to bank safes, and generally to all purposes for which locks are used.

I am well aware that permutation locks 40 have been heretofore used, having a series of disks mounted upon collars each fitting over the other, the inner one of which is mounted upon a stationary neck or stud on which it is supported and worked. And I am also aware that upon the upper ends of these collars have been secured an index 45 finger to each by which they could all be so arranged that the slot or indentation in each disk would be so placed that the lock bolt might be withdrawn from the staple so as to unlock the door. And I am likewise 50 aware that the index number of each disk

could be changed separately without changing or altering those of the others; by simply changing the position of the index finger of any of the flanged collars by means of a set screw and series of holes in the upper end of the collar. But such a change as this while it did not alter the relative numbers of the other disks, caused the party making the change to institute a series of experiments involving both time and labor 60 to determine what the index number of the collar so changed then was. Such a lock as this is at once costly, cumbersome and complicated, exceedingly liable to get out of order, and not at all adapted to common 65 purposes.

My invention consists in so arranging and combining a series of revolving slotted disks mounted upon a stationary neck or stud, that the slots of each shall be severally set 70 by each other in turn when properly operated upon by a fixed disk mounted upon a revolving shaft, so that the rear end of the lock bolt shall be free to enter the slots to permit the door to be unlocked, there being 75 but one revolving graduated index necessary to adjust the whole, and that secured to the revolving shaft. And it further relates to a new method of instantly discovering the various numbers by which the several disks 80 must be set in order to arrange their slots in a line for the reception of the end of the bolt; and which consists in perforating each disk and fixed flange of the stud, at the same angle to their slots, whereby by passing a 85 pin through a hole in the cap piece of the lock it shall enter the perforation of each in turn as their slots are respectively brought in a line with the end of the lock bolt. The number indicated on the graduated plate 90 by the arrow as the pin enters a disk, being 95 the number required to set it.

The advantages of such an arrangement will readily be perceived, as it enables the proprietor to change them as occasion should 100 require, without being compelled to enter into a long series of experiments to determine which are the proper ones to be used, thus saving both time and labor.

As my lock when applied to doors of 105 houses is not capable of being unlocked from the inside because of its peculiar construction, I have invented a new staple or catch, whereby the door may be instantly opened without retracting the lock bolt; and then 110

by the simple act of closing the door locking it again. This feature constituting another branch of my invention.

My invention further relates to a method 5 of misleading those who may be endeavoring to pick or unlock the door with burlarious intentions; and it consists in notching one of the revolving disks, (but I prefer the one next the stationary one as it is the 10 last slotted disk to be set), so that as it is caused to revolve in order to arrange the slots of the others in a line with the bolt, it will prevent them from discovering the exact moment when they are properly 15 placed, as its teeth while revolving will keep constantly striking against the inner end of the lock bolt; in this way deceiving them with the delusion that the slots have been properly arranged; and finally cause them 20 to relax their exertions and vigilance through their frequent mistakes.

To enable others skilled in the art to make, construct, and use my invention, I will now proceed to describe my improved lock more 25 in detail.

A represents a door, on the rear of which is secured by means of screws (*a*), one of my improved locks (*B*), upon the cap piece of which is cast a small circular shaped projection (*C*), through a mortise in which is firmly secured one end of a neck or stud (*D*) upon which are mounted a series of revolving disks (*c*), between each of which and rigidly connected to the stud is a flange 30 (*e*) forming a support to the disks. In all of which are cut a slot (*i*); the flanges (*e*) being so arranged and secured on the stud as that their slots shall always be in a line with the end or tang (*n*) of the lock-bolt (*E*).

Through each of the disks (*c*), and flanges (*e*), as also through the projection (*C*) of the cap piece, is pierced a hole (*m*) at an equal distance from the shaft, and in this 45 instance in a line passing centrally between the sides of the slots and diametrically through the axis of the stud, the slots being cut radially therewith, so that when the pin (*I*) is passed through these holes the slots 50 of each will be in a line with the end (*n*) of the bolt (*E*) and it be free to enter as the door is unlocked. Through the disks (*c*) are pierced a series of holes (*p*) for the reception of pins (*o*) which form adjustable 55 clutches on both sides of the disks for a purpose to be hereafter described. On the inner end of the journal (*F*) and which passes through the door (*A*) is firmly secured a disk (*f*), through which is pierced a series of holes near its periphery, they being 60 equidistant from and concentric with the axis of the disks (*c*), and like them provided with an adjustable clutch pin (*u*). Near this end of the shaft *F* between the 65 back plate of the lock and the door is formed

a shoulder (*h*) to prevent its being withdrawn from the latter, or from pushing or pressing the disk (*f*) against the disk (*c*) more than is required to bring the clutch of the latter within the sphere of action of the 70 clutch of the former; and to which it would otherwise be liable. Upon the outer end of the shaft (*F*) and which works in a bearing (*f'*) secured to the outer side of the door, is secured a graduated plate (*G*) circular in 75 form, on the periphery of which is cut a series of notches and teeth near which is engraved the corresponding number, in this instance fifty in number as seen in Fig. 1. This plate is made to rotate with the shaft 80 (*F*) as the latter is turned by means of the key (*H*), the end of the former being filed to fit the latter for that purpose; by the regulating of this plate with respect to the arrows or index (*g*) on the door the lock is 85 made to open. Through a mortise in the door immediately under the lock (*B*) is passed the key shaft (*K*) and working in bearings (*k*) on the out and inside of the door. To the inner end of this shaft is secured one end of a lever (*L*), the other extending up through a mortise in the side of the lock into a recess (*S*) formed on the underside of the lock bolt (*E*); which according to the direction in which the shaft 90 (*K*) is turned will protrude or retract the bolt (*E*) to lock or unlock the door.

M represents a plate secured to the side frame of the door by means of screws, from which project three arms (*N*) having a mortise (*v*) through their extremity for the reception of the catch bolt (*P*), the whole forming the staple into which the bolt (*E*) is passed when the door is locked. By raising the catch bolt (*P*) as seen at Fig. 6, the 100 door will be free to open without retracting the lock bolt (*E*), the former being held in its raised position by a small pin (*x*) pushed under it by means of a spring (*y*) secured to the face of the plate (*M*), until 105 the door is closed again, when the lock bolt (*E*) will press the spring (*y*) back, withdrawing the pin (*x*) from under the catch (*P*), which will then drop down through the mortise in each arm and lock the door, as 110 seen at Fig. 5. To prevent the catch (*P*) from being withdrawn altogether from the arms (*N*) a small pin (*w*) is passed through it, between the two upper arms (*N*) to limit 115 its range of motion.

Having described my improved lock in detail I will now proceed to give a description of its operation assuming for the sake of illustration the numbers for arranging the slots of the disks (*c*), of which there are 120 three, to be $48, 9\frac{1}{2}$ and $32\frac{1}{2}$ respectively, these being the numbers as the model is at present adjusted, $32\frac{1}{2}$ representing the disk next the cap of the lock, $9\frac{1}{2}$ the middle one, and 48 the one next the fixed disk (*f*) on the re- 125 130

volving shaft (F). The shaft (F) upon the inner end of which is secured the disk (f) is first caused to revolve in the direction of the arrow shown in red Fig. 1, until the 5 clutch (u) strikes against the clutch pin (o) of the first revolving disk (c), then continuing on until the other end of the clutch of the latter comes in contact with the head of the clutch pin of the second disk, carrying 10 it around until its clutch in turn strikes against the head of that of the third disk; when if there be but three of these slotted disks, the party will then be in a condition to arrange the slot of the third one in a line 15 with the slots of the flanges (e) and that of the inner end (n) of the tongue (E); for which purpose he will continue turning the shaft around in the same direction until the number 32½ on the plate (G), is brought 20 exactly opposite the point of the arrow (g), when he must immediately stop; he then reverses the motion of the shaft causing it to revolve backward twice, to bring the clutches of the disk (f) and first disk together, on 25 the other side of the clutch of the second disk, when he will continue it around until the number 9½ is brought opposite the point of the arrow (g), when the slot of the second disk will also be set; the motion of the shaft 30 (F) is again reversed and caused to describe one revolution, when the clutch of the disk f will again have been brought around to the other side of the clutch (o) on the first disk (c), which will then be turned around 35 until the number 48 on the plate (G) is opposite the arrow (g), when its slot like the others will be in a line with the tang of the lock bolt (E) and it be free to enter, as the shaft K is turned to unlock the door. 40 In adjusting the second disk after the first disk (that is the disk next the cap piece (C) of the lock) is set, the motion of the shaft is immediately reversed, as if not the slot would be carried past the bolt; and caused to 45 revolve twice before setting the second, for this reason that it requires one revolution of the disk (f) and clutch to bring it on the other side of the clutch (o) of the disk (c) next it, and another revolution to bring the 50 clutch of the disk (c) on the other side of the clutch (o) of the second disk (c) when the slot of the latter can then be set; and so in adjusting the next disk (c) only that it requires but one revolution of the disk (f) 55 to bring its clutch on the right side of the clutch of the first disk to set it.

It is not essential that the clutch (u) should be attached to the disk (f) as the same object may be effected through the 60 medium of an arm with the clutch (u) attached to it. But I prefer the former inasmuch as I am enabled to get a vast amount of changes of numbers through it, by having it perforated with a series of holes, and the 65 clutch adjustable, whereby by moving it

from one hole to another, the whole numbers to adjust the slots, would be changed each time in every disk. These can still further be changed so that they can be multiplied almost indefinitely, inasmuch as each revolving disk may if desired be pierced with a series of holes, which by the mere changing of the adjustable clutch, as in the former case from one hole into another, if the disk should happen to be the one next the 70 fixed one would also alter the numbers of all the others respectively. And so on with the other disks with this exception that any change of the clutch of the second disk from one hole to another would only involve a 75 change in the number of itself and those disks succeeding it; and the next in the same way until the clutch of the last one was changed which would simply effect its own number. And it is here to be observed that 80 the disks may be set so that the door can be unlocked by turning the shaft (K) in the first instance in the opposite direction to that which I have just now described, but in that case the same numbers would not 85 answer. The correct ones however it is an easy matter to discover as by taking the pin and inserting it into the hole of the cap (C) and exerting a slight pressure against it as you turn the shaft (K) in the direction of 90 which you desire to find the numbers, it will the moment the whole aperture (m) is brought opposite to the aperture of the projection (C) pass into it, and stop the further progress of the shaft in that direction, the 95 number indicated by the arrow (g) on the plate (G) at this point will be the required number for that disk. The motion of the shaft (F) is then reversed until the aperture of the second disk like that of the first is 100 opposite the pin which is then pressed into it, and the motion of the shaft in that direction arrested, the number indicated on the plate (G) being the required number for this disk. The number of the third being 105 110 found in the same manner, by simply reversing the motion of the shaft until the pin passes through its aperture, as in the case of the others, the numbers thus found in this instance being 23½, 16½, and 45. 115

It will now readily be perceived that my lock cannot be opened from the inside, but by raising the catch bolt (P) the door may be opened without retracting the lock bolt (E), and locked again by the closing of the 120 door as the bolt (E) having pressed the pin from under the catch (P), by pressing against the spring (y) thus permitting it to drop in place.

Having thus described my invention what 125 I claim as new and desire to secure by Letters Patent is—

1. So arranging a series of revolving slotted disks (c) upon a fixed neck or stud (D) that each in turn shall be made the 130

means of adjusting the slot of the other when operated upon by another disk (f) or its equivalent secured to a revolving shaft (F) and index (G) for the purposes described.

2. I claim altering the respective numbers of two or all the disks (c), by the simple change of an adjustable clutch from one hole to another, substantially as and for the purposes described.

3. I claim the method herein described of discovering the proper numbers to open the lock substantially as specified.

In testimony whereof I have hereunto set my hand.

WILLIAM H. AKINS.
